(No Model.)

C. SEYMOUR.
CUTTER HEAD.

No. 446,476.

Patented Feb. 17, 1891.

UNITED STATES PATENT OFFICE.

CHARLES SEYMOUR, OF DEFIANCE, OHIO, ASSIGNOR TO THE DEFIANCE MACHINE WORKS, OF SAME PLACE.

CUTTER-HEAD.

SPECIFICATION forming part of Letters Patent No. 446,476, dated February 17, 1891.

Application filed July 22, 1890. Serial No. 359,517. (No model.)

To all whom it may concern:

Be it known that I, CHARLES SEYMOUR, a citizen of Defiance, in the county of Defiance and State of Ohio, have invented certain new 5 and useful Improvements in Cutter-Heads; and I do hereby declare the following to be a full, clear, and exact description of the invention, such as will enable others skilled in the art to which it appertains to make and use the same.

My invention relates to an improvement in tenoning-machines, and more particularly to an improved cutter-head therefor, its object being to so construct the cutter-head that the 15 end of the spoke being operated upon shall be held steady while the knives are cutting.

A further object is to provide an improved cutter-head which shall be adapted to receive spokes of varying sizes.

20 A further object is to so construct a cutter-head for tenoning-machines that it shall be simple, comparatively cheap to manufacture, and effectual in the performance of its function.

25 With these objects in view the invention consists in certain novel features of construction and combinations and arrangements of parts, as hereinafter set forth, and pointed out in the claims.

30 In the accompanying drawings, Figure 1 is a sectional view of my invention. Fig. 2 is a front face view. Fig. 3 is a section on the line x of Fig. 2.

A represents the shank of the cutter-head, having an enlarged rear end, in which a socket 35 a is formed and provided internally with screw-threads, whereby the shank may be screwed upon the shaft or spindle of the machine. At the forward end of the shank A is 40 a laterally-projecting annular flange B, having dovetailed grooves or sockets b at diametrically-opposite points for the reception of two sliding blocks C, having inclined longitudinal edges adapted to conform to the 45 shape of the grooves or sockets b .

To the blocks C cutting-knives D are secured in any suitable manner, said knives being diagonally disposed relatively to the sliding blocks C. The forward end of the shank 50 is provided with a flange d , so constructed as to produce an opening for the reception of a

removable bushing E, said bushing being secured in position by means of a set-screw e , and being adapted to receive the end of a spoke being operated upon. By thus providing a bushing and connecting the same to the cutter-head so that it may be removed it will be seen that when it is desired to operate upon a spoke of larger or smaller size than the one being operated upon said bushing may be easily and quickly removed and another inserted in its place which shall be adapted to the size of the spoke to be operated upon.

The annular flange B is provided at diametrically-opposite points with perforations 65 f , which communicate with the grooves or sockets b , said perforations being adapted to receive bolts F, which latter are provided with screw-threaded ends for the reception of nuts g . The outer ends of the bolts F are provided 70 with heads h , adapted to engage one side or edge of the sliding blocks C, and thus hold said blocks fixed. By this means the sliding blocks B and the knives D may be readily adjusted at will.

Secured to the outer face of the annular flange d is a concaved circular saw G, having an opening at its center to permit the passage of the spoke to be operated upon. By means of this saw the surplus portion of the 80 spoke may be removed.

Slight changes might be made in the details of construction of my invention without departing from the spirit thereof or limiting its scope. Hence I do not wish to confine myself 85 to the precise details of construction herein set forth; but,

Having fully described my invention, what I claim as new, and desire to secure by Letters Patent, is—

1. The combination, with a cutter-head, of sliding blocks in said head, cutting-knives connected with these blocks, and a bushing for the reception of the end of the spoke, substantially as set forth.

2. In a cutter-head, the combination, with a shank having an annular flange at its forward end, of sliding blocks in said flange, cutting-knives secured to said sliding blocks, and a bushing for the reception of the end of the 100 spoke, substantially as set forth.

3. In a cutter-head, the combination, with

- a shank having an annular flange at its forward end, of cutting-knives adjustably secured to said flange, and a bushing removably connected with the forward end of the shank, substantially as set forth.
5. In a cutter-head, the combination, with a shank having an annular flange, of cutting-knives adjustably secured to said flange, a removable bushing, and a saw secured to the annular flange, substantially as set forth. 15
4. In a cutter-head, the combination, with a shank having an annular flange provided with grooves or sockets, of sliding blocks in said grooves or sockets, headed bolts passing 20 through the annular flange and adapted to engage the sliding blocks, nuts on said bolts, and cutting-knives secured to the sliding blocks, substantially as set forth.

In testimony whereof I have signed this specification in the presence of two subscribing witnesses.

CHARLES SEYMOUR.
